SOAP DISPENSER

Herman B. Freedman, Brooklyn, N. Y., assignor
to Freebur Products Company, Elizabeth,
N. J., a corporation of New Jersey

Application September 13, 1932
Serial No. 632,905

5 Claims. (Cl. 146—61)

This invention relates to soap dispensers in which cake soap is pulverized and delivered to the user.

The best grades of soap are solid at ordinary temperatures and are sold in cakes of convenient size. Germs can be conveyed from one person to another using the same cake of soap, and the use of cakes in public and semi-public wash-rooms is, therefore, objectionable if the cakes are handled. Often the soap is wasted or stolen.

Various forms of liquid soap dispensers have been devised, but liquid soap is of inferior quality and necessarily contains an adulterant for keeping it in liquid form. Devices for dispensing soap powder are inconvenient to fill, and likely to be unreliable in use.

The principal object of this invention is to provide a practical and economical soap dispenser using cake soap and dispensing it in pulverized form. Such a dispenser can be used with the best grades of soap, and has the further advantage that cakes are the most convenient form of soap for refilling dispensers.

Another object of the invention is to provide a soap dispenser with a cutter for pulverizing the soap, the cutter being of special design to keep the soap cake properly centered in the dispenser casing. This insures an even cutting of the soap, prevents edges of the soap from breaking off, and makes it impossible for the cake to become dislodged sideways so that it wedges or jams against the walls of the casing and does not feed against the cutter. Another object is to provide a combination in which the cutters are easily removed and replaced when worn. This is an important feature because any cutter will wear rapidly when pulverizing pumice soap, but the provision for convenient replacement of cutters makes it practical to use the dispenser with pumice soap.

It is an object of this invention to insure against theft of the soap dispenser by providing concealed fastening means for securing the dispenser to a supporting wall, access to the fastening means being possible only when the dispenser is open. A lock is provided to prevent opening of the device by unauthorized persons, and a countersunk door prevents forcing of the lock by prying the door open.

Another object of the invention is to provide a compact combination of elements so that the dispenser will occupy comparatively little space and can be located within convenient reach of a wash-basin.

Another object is to provide a soap dispenser

which requires cake soap of novel cross-sectional contour and which will not operate with conventional cakes of soap. Another object is to provide a cake of soap suitable for use with such a dispenser.

Other objects, features and advantages of the invention will appear or be pointed out as the specification proceeds.

In the accompanying drawings, forming a part hereof:

Fig. 1 is a front elevation of a soap dispenser designed in accordance with this invention;

Fig. 2 is a side elevation of the soap dispenser shown in Fig. 1;

Fig. 3 is a perspective view of a cake of soap 70 of special form for use in the soap dispenser shown in the other views;

Fig. 4 is a view similar to Fig. 1, but with part of the front wall and door of the casing broken away to show the interior, and with other structure behind the front wall and door shown in dotted lines;

Fig. 5 is a section on the line 5—5 of Fig. 4, with the cake of soap removed;

Fig. 6 is a section on the line 6—6 of Fig. 4; 80

Fig. 7 is a section on the line 7—7 of Fig. 6; and

Fig. 8 is a section on the line 8—8 of Fig. 4.

The soap dispenser includes a casing 11 having a filling opening closed by a door 12, which can be opened for inserting a cake of soap into the casing. A feeder platform 14 (Fig. 6) has guides 16, which bear against the inside walls of the casing and hold the feeder platform against turning or twisting in the casing, but permit 90 free vertical sliding movement of the platform.

A compression spring 18 urges the platform 14 downwardly in the casing, and the platform and spring constitute feeder means for holding a cake of soap 19 in contact with a cutter. The 95 back wall of the casing has a slot 29, and a handle 30 extends through this slot. The handle is connected to the platform 14 and is used to move the platform upwardly in the casing preparatory to inserting a cake of soap. The upper end of the spring 18 is tapered, each turn being smaller than the preceding turn so that when the spring is compressed as far as possible the turns fit within one another. Thus the tapered spring can

be compressed into a much smaller space than a spring of constant cross-section, and because of this reduction in the space required for the spring, the vertical height of the casing 11 can be made smaller than would be otherwise necessary.

Fig. 3 shows the cake of soap 19 for use in the dispenser. The cake has a curved end 20, which fits the cutter of the dispenser and assists in properly centering the cake in the casing, as will be more fully described. The other end of the cake is flat for contact with the feeder platform. A groove 21 in the face of the cake permits the soap to move past a raised surface on the inside of the casing which would obstruct the passage of the soap if there were no groove. The dispenser can be designed to require cakes of any desired cross-sectional contour, or to operate with conventional cakes.

An important purpose in requiring special soap is to insure the best operation of the dispenser. A dry soap is most effectively pulverized by the cutter of the dispenser. A wet, sticky soap may fill the cutter and even clog the discharge opening. By requiring the dispenser to be used only with cakes of soap made especially for it, there is no danger of the wrong grade of soap being placed in the casing and the operation of the dispenser impaired.

A shaft 31 (Figs. 4 and 6) is rotatably supported in the lower end of the casing 11, and a handle 32 is connected with the shaft. A cutter 34 is carried by the shaft 31. The cutter comprises a sleeve 36, which fits over the shaft 31, and a plurality of helical blades 38 and 40, connected to the sleeve and spaced apart from one another at their hub portions by spacing washers 41. The cutter 34 is operatively connected with the shaft 31 by pins 42. Other operative connections between the cutter 34 and shaft 31 can be used, but I prefer to use pins because they provide a positive connection which can not become loose so that the shaft will turn without rotating the cutter. An important advantage of the cutter installation is the convenience with which worm cutters can be removed and replaced. All cutters wear when used with abrasive soaps, such as pumice soap, but by making replacement of worm cutters convenient and economical, the use of the dispenser with pumice soap is practical. A cutter can be removed by taking out the pins 42, withdrawing the shaft 31 to the right, and then lifting the cutter out through the filling opening. A new cutter is then inserted in the casing and the shaft 31 and pins 42 replaced to hold the new cutter.

Each of the blades 38 extends as a right-hand screw and each of the blades 40 as a left-hand screw. An equal number of the right and left-hand blades 38 and 40 contact with the lower end of the soap 19. As the cutter rotates, the side thrust of the blades 38, which tends to move the soap to the right or left, depending on the direction of rotation, is balanced by an equal and opposite side thrust from the blades 40. The helical blades cut across the end of the soap, therefore, without any resultant force tending to move the soap to either side.

As a further provision for keeping the lower end of the cake of soap centered in the casing, the diameter of the cutter 34 is made smallest at its center portion and progressively large toward both ends. This form of cutter keeps the cake centered with respect to the casing and blades. The cutter construction described has the further advantage of discharging the cut or pulverized soap more centrally, so that even without a restricted delivery opening in the casing the soap would be delivered into the palm of the user's hand, and not across the hand onto the floor or basin.

The feeder platform 14 has downwardly projecting lugs 48, which hold the upper end of the cake of soap centered in the casing, between the side walls of the casing, and prevent the soap from rubbing against these walls. 80

The door 12 over the filling opening is connected to the casing by hinges 52, and has latches 54 for locking it closed. The casing has set-back edges 56 (Fig. 5) along the sides of the filling opening, and the back of the door 12 contacts with these set-back edges 56 when the door is closed. The back face of the door 12 is thus below the front surface of the casing, and the door therefore "countersunk", so that sharp instruments can not be driven between the door 12 and front of the casing to wedge the door open. A spring 58 (Fig. 4) opens the door 12 when the latches 54 are released. 85

The latches 54 are pivotally supported on studs 60 carried by a plate 62 which has its edges bent 95 forwardly and connected with the door 12 by spot welding. A spring 66 holds the latches 54 in locking position with their lower ends extending below the bottom edge of the door 12. When the door is closed, the latches 54 extend below 100 the bottom edge of the filling opening and lock the door 12 against opening. The use of two latches at spaced-apart points locks the door more securely than a single latch, because with a casing or door of thin material it would be possible to bend the casing or door sufficiently to open a single-latch lock whereas it is not possible to do so with the double spaced-apart latches 54. Both of the latches must be raised before the door can be opened because if one latch only is raised 110 it will raise one end of the spring 66 and the opposite end of the spring will force the other latch further down.

Each of the latches 54 has a lever 70 extending beyond its stud 60. These levers 70 extend to 115 the middle of the door, where one of them overlies the other. The plate 62 has a slot 72 extending from the top edge to a point slightly below the tops of the overlying ends of the levers 70. As the feeder platform 14 moves downwardly in 120 the casing 11, a trip finger 74 carried by the platform 14 moves downwardly along the slot and contacts with the levers 70. Further downward movement of the platform 14 and finger 74 causes the levers 70 to be rocked to raise the latches and 125 unlock the door 12, so that it will be opened by the spring 58. Thus, the door 12 opens automatically to permit the insertion of a new cake of soap into the casing 11 whenever the cake in the casing is almost all cut away and the feeder 130 platform has moved down to the lower end of the soap chamber.

The back wall 75 of the casing is bent along its mid-portion (Figs. 5 and 6) to provide a guide surface 78 for the cake of soap, if the lower end 135 of the cake slopes toward the back of the casing because of rotation of the cutter in that direction. The plate 62 on the back of the door 12 provides a guide surface at the front of the cake, and these front and back guide surfaces 140 hold the lower end of the cake centered over the cutter 34 so that the soap contacts with a central arc over the axis of the cutter and can not become wedged between the cutter and the front or back of the casing. 145

A raised surface 80 on the back of the plate 62 gives the cross-section of the soap chamber an irregular contour. The groove 21 in the face of the soap is in position to receive the raised surface 80. Thus the raised surface on the plate 150

62 does not prevent the cake 19 from being fed downwardly in the casing. If a conventional cake of soap, having a continuous flat face or a continuous convex surface, is placed in the casing

5 11 and the door 12 is closed, the raised surface 80 digs into the surface of the cake and prevents it from feeding downwardly against the cutter. Thus the raised surface 80 makes it necessary to use a special cake of soap which is molded or cut

10 to fit the dispenser.

The soap pulverized by the cutters drops through a delivery opening 85 at the bottom of the casing. This delivery opening is narrow, so that children can not insert their fingers through

15 the opening with the risk of being injured by the cutter blades.

The back wall 75 is detachable from the other part of the casing. The back edges 88 of the side walls of the casing extend inwardly to over-

20 lie the front face of the back wall 75. These edges 88 are secured to the back wall by screws

90. The back edge 92 of the top portion of the casing is bent over behind the back wall 75. Ears 94 on the lower parts of the side walls ex-

25 tend behind the back wall 75 (Figs. 6 and 7). When the screws 90 are removed, the back wall

can be slid downwardly with respect to the casing, the edges 88 and ears 94 serving as front and rear guides, respectively.

30 The back wall 75 is secured to upper and lower brackets 96. These brackets are hollow and are connected to a panel 97. The soap dispenser is secured to a supporting wall 98 by screws 99 ex-

35 tends through the back wall 75, hollow brackets

96, and into the supporting wall 98. The screws

99 are driven into the wall when the casing is removed from the back wall. After the back

30 wall, brackets and panel 97 have been secured to the supporting wall 98, the casing is replaced on

40 the back wall 75, and the heads of the screws 99 are not accessible for removal of the screws from

the wall 98. In order to reach the screws 99, it is necessary to take the forward part of the cas-

45 ing off the back wall 75, and this can not be done without removing the screws 90. These screws

90 are not accessible unless the door 12 is open, and this door is locked except when opened to

50 refill the casing. A lock with key can be substituted for the automatic lock on the door 12, and the door and filling opening can be in a side wall instead of the front wall, if desired.

The back of the panel 97 is recessed so that if the dispenser is to be fastened to a supporting wall by cement, instead of screws, the recess in

55 the panel houses an insert used in cementing the panel to a wall. The brackets 96 space the

casing 11 far enough from the supporting wall so that the knuckles of a person turning the handle

32 do not strike the wall.

60 The tops of the casing 11 and panel 97 are curved so that they can not be used as a con-

venient rest for glasses, cigarette butts, or other

articles which might damage the finish of the

dispenser or fall off and strike a person operating

65 the handle 32. The form of the casing, springs,

brackets and other parts of the preferred em-

bodiment can be changed, however, and various

features of the invention can be used alone or in

combination with other features, without depart-

ing from the invention as defined in the appended

70 claims.

I claim:

1. A soap dispenser comprising a casing for holding a cake of soap; a rotary cutter in the casing, the cutter having edges, a portion of which extend as a right-hand screw and another portion of which extend as a left-hand screw, the diameter of the cutter being least at its mid-portion and increasing progressively to a maximum at each end of the cutter; and feeder mechanism within the casing for moving the soap cake toward the cutter. 80

2. A soap dispenser including, in combination, a container for a cake of soap; a rotary cutter for cutting soap from one end of the cake, the cutter comprising a plurality of helical blades, including an equal number of right and left-hand helices which cut the soap simultaneously, the diameters of the helices being least at the mid-portion of the cutter and being progressively greater toward each end of the cutter; and a 90 feeder for holding the soap against the cutter. 95

3. A soap dispenser including, in combination, a casing for holding a cake of soap; means for pulverizing the soap for delivery through a discharge opening in the casing, a handle on the 100 outside of the casing for operating the pulverizing means, a panel for contact with a wall to which the dispenser is to be connected, said panel having openings to permit the passage of fastening means; hollow brackets secured to the casing and panel in register with the openings in the panel for holding the casing in spaced relation to the panel so that there is sufficient clearance for operating the handle without striking the wall; and means comprising screws extending through said hollow brackets and through the openings in said panel and having their heads within said casing and their opposite ends engaging within a supporting wall for securing said dispenser to said wall. 105 110 115

4. A soap dispenser comprising a wall panel, a soap receiving casing secured to said wall panel and including a rear supporting plate and a housing removably secured thereto said housing having therein an opening normally closed by a 120 door; a cutter rotatably journaled in said housing for pulverizing a cake of soap for delivery through a discharge opening therein; a handle at one side of said casing for operating the cutter; tubular brackets connecting said wall panel 125 and said rear plate to hold said rear plate spaced from a supporting wall far enough to permit unobstructed operation of the handle; and fastening means extending through the rear plate, tubular brackets and wall panel for securing the 130 dispenser to the supporting wall, the outer ends of the fastening means being located within said removable housing and accessible only through the normally closed opening in said housing.

5. A soap dispenser comprising a casing for holding a cake of soap; a rotary cutter mounted in said casing and comprising a shaft, a sleeve carried by said shaft and a plurality of helical blades carried by said sleeve, each blade having a toothed periphery, the effective diameter of 140 said blades progressively decreasing from each end toward the center of the cutter so that the shape of the cutter holds the soap centered on the cutter; and feeder means for urging the soap against the cutter. 145
